UNITED STATES PATENT OFFICE.

PIETRO MAGRINI, OF BELLE VERNON, PENNSYLVANIA.

COMBINED SHADE-ROLLER AND CURTAIN-POLE BRACKET.

1,258,693.

Specification of Letters Patent. Patented Mar. 12, 1918.

Application filed November 7, 1916. Serial No. 129,967.

To all whom it may concern:

Be it known that I, PIETRO MAGRINI, a subject of the King of Italy, residing at Belle Vernon, county of Fayette, and State 5 of Pennsylvania, have invented certain new and useful Improvements in Combined Shade-Rollers and Curtain-Pole Brackets, of which the following is a specification.

This invention relates to a combined shade 10 roller and curtain pole bracket and has for its object to provide a bracket of such class, in a manner as hereinafter set forth, with means for supporting a curtain pole and shade roller and further provided with 15 means whereby the support for the shade roller can be adjusted for rolls of different lengths.

A further object of the invention is to provide a bracket of the class referred to 20 with a pole support in a manner as herein- after set forth whereby the curtain pole can be adjustably supported with respect to the window frame, that is to say brought closer or removed away therefrom when desired.

25 A further object of the invention is to provide a bracket of the class referred to with a shade roller support capable of being adjusted to provide for the different lengths of support and locked in a position 30 to which it has been adjusted.

Further objects of the invention are to provide a bracket for the purpose set forth which is simple in its construction and arrangement, strong, efficient and convenient 35 in its use, readily secured to the window frame, durable, and inexpensive to manufacture.

With the foregoing and other objects in view the invention consists of the novel construction, combination and arrangement of 40 parts, as hereinafter more specifically described and illustrated in the accompanying drawings, wherein is shown an embodiment of the invention, but it is to be understood that changes, variations and modifications can be resorted to which come within the scope of the claim hereunto appended.

In the drawings wherein like reference characters denote corresponding parts 45 throughout the several views:

Figure 1 is an elevation of a portion of a window frame showing the adaptation therewith of a combined shade roller and curtain pole support bracket in accordance 55 with this invention.

Fig. 2 is a top plan view of a bracket.

Fig. 3 is a section on line III—III of Fig. 2.

Fig. 4 is a section on line IV—IV, Fig. 1.

Fig. 5 is a section on line V—V, Fig. 2.

Referring to the drawings in detail 1 denotes a portion of a window frame and to the sides thereof is connected the combined shade roller and curtain pole support bracket through the medium of an angle shaped 65 arm 2 formed with openings 3, for the passage of securing devices 4.

Fixedly secured to the front of the arm 2, intermediate the ends thereof, is an elongated oblong housing 5, which is rectangular in vertical section, and has the front wall thereof provided with a longitudinally extending slot 6 of the same length as the length of the said wall. The housing 5 has its rear wall fixedly secured to the bracket 70 2.

The inner end of the housing 5 is open, and the outer end closed by a plate 7, provided centrally with a vertically disposed rectangular slot 8. Mounted in the housing 5 is a slide 9 having projecting outwardly 75 therefrom and through the slot 6, a shank 10, with which is formed integral an arm 11 of greater width than the width of the shank so that the arm will overlap the outer face of the front wall of the housing 5. 80 The outer end of the arm 11 is provided with means, as at 12, to constitute a bearing for the pintle of the shade roller.

Extending through the slot 8 is an elongated bar 13 having one edge provided 90 with spaced teeth 14. The inner end of the bar 13 is reduced as at 16, and extended through an opening 18 in the slide 9. The free terminus of the reduced end 16 is upset, as at 19, to prevent the bar from pulling 95 through the slide 9. The diameter of the reduced end 16 of the bar 13, with respect to the opening 18, is such as to provide what may be termed a swivel connection between the bar and slide and which will permit of the bar shifting when occasion so requires.

The outer end of the bar 13 has a finger grip 21. The function of the bar 13 is to 100 adjust the position of the slide 9 to provide for different lengths of shade rollers and when the bar 13 is turned in an upright position it can be moved longitudinally with respect to the housing 5 and when the slide 9 has been adjusted to the desired position, 110

the bar 13 is given a quarter turn so that the plate 7 will engage between a pair of teeth 14, and lock the bar so as to maintain the slide 9 in the desired position.

- 5 The rear wall of the housing 5, near the outer end thereof, has secured thereto a socket forming member 22, and adapted to receive the vertically disposed inner portion 23 of an outwardly projecting supporting arm, which not only includes the vertical inner portion 23, but also an upwardly curved intermediate portion 24 and a horizontally disposed channel-shaped portion 25 having the sides thereof at the outer end inset and further having the forward end of the bottom formed with a vertically disposed ledge 26. The top of the channel shape portion, at each side has a vertically disposed abutment lug 27.
- 10 Shiftably mounted in the channel shaped portion 25 is a slide 28 provided at its rear end with a T-shape head 29 which projects out of the channel shape portion 25 and arranged within the latter is a spring 30 which
- 15 maintains the slide against the top thereof and furthermore locks the slide in the position to which it has been adjusted.
- 20 Shiftably mounted in the channel shaped portion 25 is a slide 28 provided at its rear end with a T-shape head 29 which projects out of the channel shape portion 25 and arranged within the latter is a spring 30 which
- 25 maintains the slide against the top thereof and furthermore locks the slide in the position to which it has been adjusted.

The lugs 27 in connection with the heads 29 prevent complete withdrawal of the slide 28 unless the latter is forced downwardly to compress the spring 30.

The outer end of the slide 28 has a semi-

circular extension 31 which provides a seat for a curtain pole.

What I claim is:—

35 A bracket for the purpose set forth comprising an elongated oblong housing having its front wall provided with a longitudinal slot, a plate closing the outer end of said housing and having a vertically disposed rectangular slot, a slide mounted in the housing and having a shank projecting through the longitudinal slot, and carried by and of greater width than the shank and provided with means to constitute a bearing for the pintle of a shade roller, an elongated bar having one edge provided with spaced teeth and extending through said rectangular slot into said housing, said bar having a reduced inner end extending through said slide, said end upset to provide a swivel connection between the bar and slide, said bar capable of being shifted to adjust the slide and to overlap one of the walls of said rectangular slot to maintain the slide in adjusted position, and a handle on the outer end of the bar.
